HEEL ATTACHING MACHINE

Edward F. Small, Newton, Mass., assignor to
 Compo Shoe Machinery Corporation, Boston,
 Mass., a corporation of Delaware

Application May 16, 1947, Serial No. 748,380

7 Claims. (Cl. 12—42)

1

This invention relates to screw inserting machines and more particularly to a machine for securing heels to shoes.

It is customary to initially secure a heel to a shoe, while the shoe is mounted upon its original last, by drilling a lead hole through the heel seat of the shoe and into the positioned heel and thereafter driving a woodscrew into the hole to draw the parts together.

Attempts have been made to drive a screw into the shoe and heel without first forming a lead hole and I have found that this practice is very satisfactory providing the body diameter of the woodscrew is smaller than that of the screws generally used when a lead hole is formed.

A general object of this invention is to provide an improved machine for securing heels to shoes by means of woodscrews, while the shoes are mounted upon their original lasts, which is simple in construction, rapid and simple to operate, and which reduces the cost of such operation while increasing the output per machine.

Another object of the invention is to provide a screw inserting machine which is largely automatic in operation and which, when used with prepared lasts, will drive the woodscrews to a definite depth without marring the screw heads.

A further object of the invention is to provide a screw inserting machine having a single screw driving spindle which is rotated in a screw driving direction to cause it to be moved towards the work and in a reverse direction to move it away from the work thus obviating the necessity of expensive stop mechanisms.

A still further object of the invention is to provide a screw inserting machine having a screw driving spindle construction which allows rotation of the spindle to be reversed when the screw has been driven to the desired depth, the screw driver to be moved away from the work and to be held non-rotative until it is withdrawn from its driving connection with the screw driven into the work.

Other objects of the invention will in part be obvious and will in part appear hereinafter.

The invention accordingly comprises the features of construction, combination of elements, and arrangement of parts which will be exemplified in the construction hereinafter set forth and the scope of the invention will be indicated in the claims.

For a fuller understanding of the nature and objects of the invention reference should be had to the following detailed description taken in

2

connection with the accompanying drawing, in which:

Fig. 1 is a front elevation, partly in section, of a screw inserting machine embodying features of my invention;

Fig. 2 is a side elevation, partly in section, of the machine;

Fig. 3 is a partial sectional plan view taken along lines 3—3 of Fig. 2;

Fig. 4 is a fragmentary sectional view showing the last thimble mounted upon the last support and the spindle in position ready to drive a screw;

Fig. 5 is a fragmentary plan view taken along lines 5—5 of Fig. 4;

Fig. 6 is a fragmentary view, partly in section, similar to Fig. 4 but showing the screw driver spindle starting to drive a screw into the shoe and heel;

Fig. 7 is a view similar to Fig. 6 but showing the screw driver spindle after its rotation has been reversed and the screw driver disengaged from driving connection with the screw driven into the shoe and heel;

Fig. 8 is a schematic wiring diagram of the electrical elements of a machine; and,

Fig. 9 is a fragmentary plan view taken substantially along line 9—9 of Fig. 2.

Referring to the drawing, there is shown a machine for attaching heels to shoes the general construction of which is similar in many respects to the machine described in my co-pending application Serial No. 695,431, filed in the United States Patent Office on September 7, 1946, now

Patent No. 2,449,333 issued September 14, 1948.

The machine of this invention comprises a base casting 10 to which the top casting 11 is secured by the bolts 12 to form a frame to support and house the machine mechanism.

The underside of the top casting 11 is provided with a depending boss 13 to which a bracket 14 is secured by the screws 15. An extension of the bracket terminates to form a boss 16 which is bored to receive a bushing 17 in which the lower end of the screw-driver spindle 18 is journaled.

The upper end of the screw-driver spindle is journaled in a bushing 19 which is pressed into a cap 20 secured by the screws 21 to the underside of the top casting 11 in alignment with a bore formed therein and the hollow last supporting pin 22 is secured by the screws 23 to the upper side of the top casting in alignment with the screw-driver spindle.

The screw-driver spindle is adapted to be rotated and to accomplish this the pulley 24 se-

cured thereto is belted to a pulley 25 driven by the shaft of an electric motor 26 which is secured to the base casting.

The screw-driver spindle is also adapted to be reciprocated and this is effected by and is dependent upon rotation of the spindle.

As best shown in Figs. 2 and 3, a worm 27 is keyed to the spindle 18 and is held in place by the collars 28 and 29 against which the inner races of the ball bearings 30 and 31 are jammed by the lock nuts 32 and 33 threaded to the spindle.

The outer races of the ball bearings fit within vertical bores formed in a gear housing 34 which is forced to partake of any reciprocating movement of the spindle due to the outer race of the ball bearing 30 being locked against the shoulder 35 of the gear housing by the cap 36.

The gear housing 34 is prevented from rotating with the spindle 18 by a key 37 which is formed integral with the housing and which fits and slides in a spline 38 formed in the bracket 14.

The gear housing is also provided with the horizontally extending bores 39 in which is journaled a shaft 40 having a worm wheel gear 41 keyed thereto which meshes with and is rotated by the worm 27. The shaft 40 extends from each end of the gear housing and set screwed to each extension is a crank disc 42 having threaded thereto a crank pin 43. With this construction the cranks revolve as long as the spindle 18 is rotated.

Each side of the bracket 14 is provided with a horizontally extending shelf like portion 44 and secured thereto are wear plates 45 which are engaged by the crank pins 43 thus causing the entire gear housing and spindle to be moved when the spindle 18 is rotated.

A cylindrical clutch portion 46 is secured by a taper pin 47 to the upper end of the spindle 18 and is internally threaded with a left hand thread of coarse pitch. As shown in Figs. 4, 5 and 6, the upper surface of the clutch portion is cut away to leave an upstanding segment 48 which engages with a dog pin 49 extending from the screw driver shaft 50 which threads into the clutch section.

The screw-driver bit 51 is threaded into the shaft 50 so that the bit can easily be replaced.

The last L upon which the shoe S is mounted, and all lasts intended for use with the machine are provided with a screw receiving recess in the form of a metal last thimble T which is pressed into the last and seats against a washer W having an opening of smaller diameter than the thimble so as to provide a shoulder to engage against the top of the last-supporting pin 22 and to take the heel clamping pressure. Regardless of the size of the last, the washer W is located a definite distance away from the heel seat portion and, as will be later understood, this allows the heel attaching screw F to be driven to a definite depth.

The heel clamping device comprises a heel engaging member 52 which is swingably mounted upon the pivot ends of the screws 53 which are threaded into the U-shaped ends 54 of the arm 55. The other end of the arm 55 is bifurcated to fit over a lever 56 and is pivoted thereto at 57. A screw 58 prevents the arm from moving with respect to the lever while clamping a shoe and also serves to adjust the position of the arm to accommodate different styles of heels.

The lever 56 is pivoted at 59 to the bifurcated end of a plunger 60 which is freely movable in a bore 61 formed in the bracket 14. The plunger

has portion 62 of reduced diameter which passes through a hole 63 formed in line with the bore 61 and a compression spring 64 serves to upwardly bias the plunger, the lever 56 and its associated parts.

The nut 65 serves to limit the extent that the plunger can be raised under the influence of the spring 64.

The horizontally disposed end 66 of the lever 10 56 is bifurcated to straddle the spindle 18 and gear housing 34 and each leg of the lever is pivotally joined to a treadle rod connector 67 by the clevis pins 68. The upper ends of the treadle rods 69 are screw threaded into the connectors 67 and the lower ends are threaded into the clevises 70 which are pivotally connected to a rod 71 extending from and crosswise to the treadle 12.

The treadle 72 is pivotally mounted upon the shaft 73 held by the bracket 74 secured to the base casting 10 by the bolts 75.

When the treadle 12 is in its upper position the arm 55 is in a position remote from the last supporting pin 22, as shown by dot dash lines in Fig. 2, and allows the shoe and last to be placed easily upon the pin.

In operation of the machine, the operator drops a woodscrew F, preferably of the recessed head type, head down into the hollow last supporting pin 22 where it comes to a rest upon and centers 30 with the screw driver bit 51. A shoe with its last is placed upon the last pin, the heel is positioned and the treadle 72 depressed which first causes the lever 56 to move about its pivot until the heel engaging member 52 contacts the heel. Further depression of the treadle overcomes the bias of the spring 64 and the complete heel clamp moves downwardly to clamp the heel H to the shoe S and the last is firmly pressed downwardly until the washer W within the last is pressed 40 against the top of the last supporting pin 22. The heel clamp is prevented from moving rearwardly by the pin 76 which is pressed into the lever 56 and which engages against the block 77 screwed to the top casting as shown in Figs. 2 and 9.

When the heel is clamped, the operator depresses the button 78 of a switch 79 which, as shown in Fig. 8, energizes the coil of a magnetic contactor 80 to start the motor 26 and this causes 50 the spindle 18 to be rotated in a screw driving direction. As the spindle is rotated it is also moved towards the shoe and heel as the crank pins 43 press against the wear plates on the bracket 14 and cause the complete gear housing 34 to lift.

Since the threaded connection between the screw driver shaft 50 and the clutch section 46 is of opposite hand to the screw to be driven, the shaft 50 does not rotate during a portion 60 of the first revolution of the spindle 18 but is simply elevated until the dog pin 49 is engaged by the segment 48 on the clutch section which acts as a driver.

After engagement of the dog pin with the clutch section segment 48, the spindle 18 and the screw driver shaft and bit continue to rotate and be moved upwardly as a unit and the screw F is driven into the shoe and heel.

When the screw is driven to the correct depth 70 into the shoe and heel, rotation of the spindle 18 is reversed. This is accomplished by a double pole double throw switch 81 which is held upon a bracket 82 bolted to the base casting 10 and which is actuated by the collars 83 which are 75 adjustably secured to a rod 84 threaded and

locked to a plate 85 extending from the cap 36 on the gear housing 34.

When the rotation of the spindle 18 is reversed, the screw driver shaft 50 does not rotate as it simply threads into the clutch section 46 until the crank pins 43 have rotated sufficient to allow the gear housing and spindle to lower an amount sufficient to allow the screw driver bit 51 to disengage from its driving connection with the screw head as indicated by Fig. 7. After the screw driver bit has cleared the screw head, it again rotates with the spindle 18.

As the gear housing reaches its lowest position the reversing switch 81 is again actuated and as the operator hears its action he allows the button 18 of the switch 79 to be released and the motor is deenergized.

The foot treadle is released and the shoe with its attached heel is removed and the machine remains ready to operate upon another shoe.

Since certain changes may be made in the above construction and different embodiments of the invention could be made without departing from the scope thereof, e. g., a pawl and ratchet or other one way clutch device could be substituted for the threaded connection between the screw driver spindle 18 and the screw driver shaft 50, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a screw inserting machine, a work support, a rotatable spindle, a screw driver mounted upon said spindle, means for rotating said spindle and screw driver in a screw driving direction and for moving such assembly towards said work support, means for reversing the direction of rotation of said spindle and for allowing it to move away from said work support, and means for preventing reverse rotation of the screw driver mounted upon said spindle until said spindle has moved away from said work support a distance sufficient to disengage said screw driver from driving engagement with a screw.

2. In a screw inserting machine, a work support, a rotatable spindle, a screw driver mounted upon said spindle and rotatable therewith through a lost motion connection, means for rotating said spindle and screw driver in a screw driving direction and for moving such assembly towards said work support, and means for reversing rotation and movement of said spindle when it has moved towards said work support a distance sufficient to drive a screw into work held thereto, whereby said lost motion connection between said spindle and said screw driver will allow said screw driver to be held non-rotative during reverse rotation of said spindle until said spindle has moved away from said work support a distance sufficient to withdraw said screw driver from driving engagement with the screw driven into the work.

3. In a screw inserting machine, a work support, a rotatable spindle, a screw driver mounted upon said spindle and rotatable therewith through a one-way clutch, means for rotating said spindle and screw driver in a screw driving

direction and for moving such assembly towards said work support, and means for reversing rotation and movement of said spindle when it has moved towards said work support a distance sufficient to drive a screw into work held thereto, whereby said one-way clutch will allow said screw driver to be held non-rotative during reverse rotation of said spindle until said spindle has moved away from said work support a distance sufficient to withdraw said screw driver from driving engagement with the screw driven into the work.

4. In a screw inserting machine, a work support, a rotatable spindle, a screw driver, said screw driver being rotatably threaded to one end of said spindle with a thread having a helix rotation opposite to that of the screws to be driven, means for limiting rotation of said screw driver with respect to said spindle, means for rotating said spindle and said screw driver in a screw driving direction and for moving such assembly towards said work support, and means for reversing rotation and movement of said spindle when it has moved towards said work support a distance sufficient to drive a screw into work held thereto, whereby said screw driver will be held non-rotative during reverse rotation of said spindle until it is moved away from said work support a distance sufficient to withdraw it from driving engagement with the screw driven into the work.

5. In a heel attaching machine, the combination comprising, a frame, a hollow last pin mounted upon said frame, means for clamping a heel to a shoe on a last supported by said last pin, a screw driving spindle in alignment with said last pin, power operated means for rotating said spindle in a screw driving direction, means dependent upon rotation of said spindle in a screw driving direction for moving it towards and to drive a screw into the shoe and heel supported by said last pin, and automatically operated means for reversing the direction of rotation of said spindle and for moving it away from the shoe and heel supported by said last pin.

6. In a heel attaching machine, the combination comprising, a frame, a hollow last pin mounted upon said frame, means for clamping a heel to a shoe on a last supported by said last pin, a rotatable spindle in alignment with said last pin, a screw driver held to said spindle, means for rotating said spindle and said screw driver in a screw driving direction and for moving said spindle towards the shoe and heel supported by said last pin to drive a screw therein, means for reversing the direction of rotation of said spindle and for moving it away from the shoe and heel, and means for preventing reverse rotation of said screw driver until said spindle has moved away from the shoe and heel a distance sufficient to withdraw said screw driver from driving engagement with the screw driven therein.

7. In a heel attaching machine, the combination comprising, a frame, a hollow last pin mounted upon said frame, means for clamping a heel to a shoe on a last supported by said last pin, a housing slidable on said frame, a screw driver spindle journaled in said housing, one end of said spindle extending into said hollow last pin, a screw driver rotatably secured to the end of said spindle extending into said hollow last pin, means for limiting rotation of said screw driver with respect to said spindle, a shaft journaled in said housing and extending at a right angle to said spindle, gearing connecting said shaft and said

spindle, means for rotating said spindle in a screw driving direction, a crank mounted on the end of said shaft, means engaging said crank to cause said housing and spindle to move towards the heel clamped to the shoe supported by said hollow last pin as said spindle is rotated, means for reversing the direction of rotation and movement of said spindle, when it has moved towards the heel a distance sufficient to drive a screw therein, and means for preventing reverse rotation of said screw driver while it is in engagement with a screw driven into the shoe and heel.
